UNITED STATES PATENT OFFICE.

HENRY G. VOIGHT, OF NEW BRITAIN, CONNECTICUT, ASSIGNOR TO SARGENT & COMPANY, OF NEW HAVEN, CONNECTICUT, A CORPORATION OF CONNECTICUT.

LOCK.

1,207,450.

Specification of Letters Patent.

Patented Dec. 5, 1916.

Original application filed March 13, 1915, Serial No. 14,124. Divided and this application filed December 4, 1915. Serial No. 65,058.

To all whom it may concern:

Be it known that I, HENRY G. VOIGHT, of New Britain, county of Hartford, and State of Connecticut, have invented certain new and useful Improvements in Locks, of which the following is a full, clear, and exact description.

This invention relates to locks and more especially to master keyed cylinder locks.

My improved cylinder can be used advantageously with mortise locks of the type disclosed in my application, Serial No. 14,124, of which the present application is a division, and with various other types of mortise locks where an emergency key or a shut-out key is used in addition to the change key.

One of the primary objects of the present invention is to provide a master keyed cylinder lock having a plurality of rollbacks, and a plurality of keys, said rollbacks rotatable together by any of said keys, and one of said rollbacks being movable radially of the cylinder lock, and of the other rollback by one of said keys, which is of less length than the keyway but not by another of said keys.

The invention also has in view the general improvement of locks of the master keyed cylinder type.

To these and other ends, the invention consists of the novel features and combinations of parts to be hereinafter described and claimed.

In the accompanying drawing, Figure 1 is a rear elevation of a cylinder lock embodying my improvements, showing a portion of the mortise lock mechanism described in my application Serial No. 14,124 hereinbefore mentioned; Fig. 2 is a section on line 2—2 of Fig. 1, showing the master key (maid's key) in the lock; Fig. 3 is a sectional view of the rear portion of the cylinder lock showing the rollbacks actuated by the master key; Fig. 4 is a view generally similar to Fig. 2, showing the rollbacks actuated by the emergency key; and Fig. 5 is a view similar to Fig. 1, showing the rollbacks actuated by the emergency key.

My improved cylinder lock comprises a case 25 containing a key plug 54 surrounded by an eccentric sleeve 55, and the key plug and sleeve are adapted to be locked to the case by the customary sectional pin tumblers 56. The arrangement is such that

at least one key will rack the pin tumblers so as to rotate the key plug individually, while at least one key will rack the pin tumblers so as to rotate the key plug and sleeve together. In this last case, the key plug rotates on the axis of the sleeve rather than its own axis, and it is to be noted that the axis of the sleeve is disposed somewhat above the axis of the key plug. A dog or rollback 57 is secured to the rear end of the key plug by screws 58, and is provided with a radial arm carrying a projection 59, which, in the present case, is adapted to engage a projection 44 on a tumbler 42. The projection 59 on the rollback 57 extends rearwardly from said rollback, as best shown in Fig. 2. Another dog or rollback 60 is adapted to rotate on the axis of the sleeve 55 and comprises a ring-like body portion loosely encircling the rear extremity 75 of the sleeve and carrying a radial arm 61 with rearwardly directed side flanges, between which the arm of the rollback 57 is confined. The rollback 57 may be termed the emergency rollback, because it is adapted to operate the emergency tumbler 42, while the rollback 60 may be termed the regular or ordinary rollback because it is adapted to engage an ordinary tumbler 41 of the mortise lock mechanism. It will be understood that the operating movement of the rollback 60 is imparted to it by reason of the fact that it is interlocked with the arm of the emergency rollback 57, as described, said emergency rollback being rotatable by all of the keys adapted to the lock because it is fixed to the key plug. The interlocking of the arm of the emergency rollback between the flanges 62 of the regular rollback permits independent radial movement of said rollbacks when the key plug rotates on its own axis instead of on the axis of the sleeve, as will be understood.

In Fig. 2, I have shown a key 64 inserted into the cylinder lock. In the parent application, Serial No. 14,124, this key is referred to as a maid's key, but it might be used just as well as a change key, and, in the present case, it will be referred to by the latter term in order to simplify the description. In the particular case illustrated, this key racks the pin tumblers in such a manner as to interlock the key plug and sleeve, and release the sleeve from the case so that the plug and sleeve are free to rotate on the longitudinal

axis of the sleeve. In actuating the roll-backs 57, 60, they both rotate on the axis of the sleeve and maintain the same relation to each other so that when the key has been turned through half a revolution, the roll-backs will actuate the respective tumblers 42, 41 in the manner shown in Fig. 3. The key 65, shown in Fig. 4, is referred to herein as an emergency key, and it is adapted to 10 rack the pin tumblers 56 in such a manner as to release the key plug individually so that it can rotate on its own axis. In actuating the cylinder lock by the emergency key, as shown in Figs. 4 and 5, the sleeve remains 15 stationary but both roll-backs 57, 60 are rotated because of the interlocking engagement of the roll-back 60 with the operating roll-back 57. Here the two roll-backs rotate on different axes, however, the axis of rotation 20 of 57 being lower than that of 60, so that when the key is turned in the lock the roll-back 57 will be moved radially outward and downward relatively to the roll-back 60. In this manner, the projection 59 on roll-back 25 57 is moved outward in the grooved arm of roll-back 60 so that it approaches the extremity of said arm more nearly than in the case shown in Fig. 3. Thus, the roll-back 57 depresses the tumbler 42 to a much 30 greater extent when the emergency key is used (Fig. 4) than when the change key is used (Fig. 3). As the key is moved back to the initial position the projection 59 is moved radially inward until it again occupies 35 its original position. The difference in the amplitude of movement of the tumbler 42 when actuated by the two different keys is utilized in giving the lock the necessary emergency release and shut-out functions as described in the parent application, 40 although it is manifest that the cylinder herein described may be used in connection with various types of locks, where different keys have different functions.

45 It will be observed that by my improved construction, I am enabled to move one roll-back radially of another by a short key which is of less length than the keyway and does not pass through either of said roll-backs. It will also be observed that the member 57 or its equivalent has a double function, that is to say, it serves as an operator for the roll-back 60 or its equivalent, and also as an additional roll-back.

55 Various changes in the details of the construction may be adopted without departing from the scope of the invention as defined in the claims.

What I claim is:

60 1. The combination with a cylinder lock and a plurality of keys therefor, of a plurality of roll-backs on said cylinder lock all rotatable by all of said keys, one of said roll-

backs being movable radially of the other by a short key which is of less length than the keyway and means to prevent movement of said first roll-back radially of such other roll-back by another of said keys; substantially as described.

2. A cylinder lock having a plurality of roll-backs permanently secured to the rear end thereof and a plurality of keys, one of said roll-backs being located at the rear of the other and having a rearwardly directed bolt-operating projection, and means for moving said last-named roll-back radially of the other roll-back by one of said keys said roll-backs being immovable relatively to each other by another of said keys; substantially as described.

3. The combination with a cylinder lock and a plurality of keys therefor, of two roll-backs on the rear end of said cylinder lock, both rotatable by all of said keys, one of said roll-backs located rearwardly of the other and having a rearwardly directed bolt-operating projection, the other roll-back projecting radially beyond the first-named roll-back, and the first roll-back being movable radially of the second roll-back by a short key which is of less length than the keyway; substantially as described.

4. A cylinder lock having a roll-back with a radial guide-way, a roll-back projection engaging said guide-way, and a key for positively moving said roll-back projection outwardly and inwardly in said guide-way; substantially as described.

5. A cylinder lock having a roll-back with a radial guide groove, a second roll-back at the rear of the first having an arm engaging said groove, and a rearwardly directed bolt-operating projection on said arm, and a key for moving said bolt-operating projection inward as well as outward in said groove; substantially as described.

6. In a cylinder lock, the combination of a key plug, a sleeve, a roll-back fixed to the key plug, and a roll-back loose on the sleeve, actuated by said first roll-back; substantially as described.

7. A cylinder lock having a plurality of roll-backs permanently secured to the rear end thereof, a plurality of keys, and means for giving one of said roll-backs a radial movement relatively to the other by one of said keys, said first roll-back being moved positively in an inward direction relatively to said second roll-back by means of said key as well as in an outward direction, but being immovable relatively to said second roll-back by another of said keys; substantially as described.

In witness whereof, I have hereunto set my hand on the 2nd day of December, 1915.

HENRY G. VOIGHT.
